UNITED STATES PATENT OFFICE.

CLYDE A. COOK, OF BLOOMSBURG, PENNSYLVANIA.

LOOM FOR AND METHOD OF WEAVING FABRICS.

Application filed May 22, 1920. Serial No. 383,450.

To all whom it may concern:

Be it known that I, CLYDE A. Cook, a citizen of the United States, residing at Bloomsburg, in the county of Columbia and State of Pennsylvania, have invented certain new and useful Improvements in Looms for and Methods of Weaving Fabrics, of which the following is a specification.

This invention relates to a loom constructed to weave superposed independent fabric webs simultaneously.

I am aware that separate webs have been simultaneously woven on unit machines but, in such cases, the machines, in mechanism, are the equivalent of two or more looms; or are designed for weaving a tube and thence splitting the tube longitudinally on opposite sides to produce the two separate fabric webs. However, in the case of splitting a tube the edges are left unfinished which is especially disadvantageous, particularly in fine fabrics such as georgettes and the like.

The principal features of the novelty of this invention over the present state of the art are the provision in a single loom, of more than one independent shed, each shed having its own warp and served by several shuttles alternately interchanging between the several sheds, whereby several superposed fabric webs are produced which are interconnected by only half as many filler threads as is the case in weaving on the usual bag or tube loom, and when these filler threads are severed two independent selvage edge fabric webs are the result.

The invention further provides the necessary mechanism for crossing the shuttles through the sheds to obtain the above result, and, in addition, is equipped with protector mechanism which prevents a smash due to the non-arrival of any shuttle.

In the drawings:

Figure 1 is a front view showing the shuttle boxes, lay and attendant mechanism, parts 27 to 32 having been omitted for the sake of clearness.

Fig. 2 is a plan view of the shuttle race, and showing the slitter knives in position for severing the filler connecting the separate webs.

Fig. 3 is a diagrammatic longitudinal section of the loom.

Fig. 4 is a perspective view of one shuttle box and its protective mechanism, bracket 29 being omitted for clearness of illustration,

Fig. 5 is a diagrammatic view showing the cycle of the shuttle.

Fig. 6 is a diagrammatic view showing the evolution of the two independent fabric webs, through three successive double shed formations.

Fig. 7 is an enlarged front elevation of the left hand shuttle box.

Fig. 8 is a top plan view thereof.

Fig. 9 is a fragmentary rear elevation of the shuttle box guide end with the picker just leaving the same.

Fig. 10 is a perspective view of the double picker.

In detail: The construction of the loom 70 is substantially the same as the usual cam loom, comprising the side frames 1 carrying the loom beams 2 and 3 on which the warp for the independent sheds is wound. The warp from beam 2 runs over the whip roll 75 4 while the warp from the loom beam 3 runs over the whip roll 5; and the warps then run under and over the rolls 6 and 7 respectively and pass through the heddles carried by the harness 6' whereby the two 80 independent superposed sheds A and B are formed. A reed 7' common to both sheds and mounted by the lay 8 is carried by the lay swords 9 for beating up the filler. The top of the lay 8 forms the 85 shuttle race for the lower shed, while an independent member 10 carried by the mounting for the reed 7' forms the shuttle race for the upper shed A, and cooperates with supplemental race ways or filler shelves 90 10' to form a substantially continuous support for the shuttle during travel.

In thus providing two sheds two superposed independent fabric webs may be woven on a unit machine by crossing the shuttles 95 through the upper and lower sheds as will be hereinafter described in connection with the shuttle mechanism. However, after the webs are formed as indicated at C and D they are taken off the loom through the pairs 100 of rollers 11 and 12 and through a series of guide rollers, over the respective sand rollers 16 and 17 and finally wound on the cloth rolls 18 and 19 at the front of the loom.

At each side of the loom is the usual 105 shuttle mechanism including the picker mechanism which comprises the picker sticks 20 and 21 which actuate the various picker blocks or butts carried by the shuttle boxes E and F each of which has three inde- 110

pendent shuttle receiving compartments as shown. These shuttle compartments move up and down through the usual motions of the loom as in the case of the ordinary loom 5 of the cam type. At the front of the lay are mounted the protector rods 22 and 22' carrying protector arms 23, 24, 25 and 26 and daggers 23" which operate in the usual manner to prevent a smash if any shuttle 10 fails to properly arrive in its respective box.

It will be seen that with the foregoing arrangement of protector mechanism full protection is guaranteed for the reason that 15 when one shuttle is in the box it operates its pair of protectors, while the other pair of protectors cannot be operated if its shuttle fails to reach its box; whereas if only one protector was used for each box protection would be given only in the event that both shuttles fail to reach their boxes, 20 for if one shuttle reaches the box (regardless of which box it is) the protector rod is operated, and the lay is not stopped and a 25 "smash" is the result.

As previously set out there are two sheds A and B being the upper and lower shed respectively and each shed being entirely independent of the other except for the fact 30 that they are served by the same reed and by interchanging shuttles. In weaving the usual tube it is customary for the shuttles to travel through the upper shed, back through the lower shed and again through 35 the upper shed, thus producing an adequate filler so that a tube is the result. In the present invention, however, the shuttles are crossed between the sheds so that the result, while a tube, is nevertheless an upper and 40 lower web connected by only half as many filler threads at the side as is the case with the usual tube. This is accomplished in the following manner: Referring to Fig. 1 the shuttles are in the middle compartments of 45 the movable shuttle boxes E and F with the shuttle box on the right hand, namely F, in a position to deliver the shuttle from its middle compartment through the lower shed while the shuttle box E on the left hand side 50 is in a position to deliver the shuttle in its middle compartment through the upper shed. These shuttles are designated X and Y (see Figures 1 and 5) and cross in opposite directions, Y going to the lower shelf of 55 box E from right to left through the lower shed B on the race of lay 8 and X crossing from the left to right through the top shed A on the top shuttle race 10 to the upper shelf or compartment of box F, from which 60 each shuttle returns on the next pick to the center shelf or compartment of the respective boxes from which they were originally picked, then the boxes change their positions, box F going up and box E going 65 down when, again, the operation of crossing

the shuttles through the sheds is repeated, this time shuttle Y crossing through the top shed A on the top shuttle race 10 to the top shelf or compartment of box E while shuttle X crosses through the lower shed to 70 the lower shelf or compartment of box F after which each shuttle again is returned to the center shelf or compartment of their respective shuttle boxes, the boxes then changing to their first position, shuttle box F 75 going down and shuttle box E going up, this operation being continued repeatedly during the weaving of the goods. It is to be noted in this connection that each shuttle box consists of three shelves or shuttle receiving 80 compartments, the center shelf or compartment of each being for the purpose of changing the shuttles from one piece of goods to the other, while the top shelf or compartment is to receive and return the opposite 85 shuttle by passing it through shed A of the upper piece of goods and the lower shelf or compartment is to receive and return the opposite shuttle by passing it through shed B of the lower piece of goods. In this way 90 the two webs are woven with only half as many filler threads connecting the two as would be the case in a bag or tube loom. Mounted on the lay and carrying the top shuttle race 10 are the U-shaped members 27 95 Figures 2 and 4 which have, at their bend the knife blades 28 which are located in such a position as to be in line with the filler threads connecting the two webs of fabric so that immediately upon the weaving of the 100 fabric these filler threads connecting the two superposed webs are severed thus making the two superposed webs entirely independent from each other. This loop is of proper dimensions to permit freedom of 105 filling to bind the selvage of the goods together for a woven length, in practice, of approximately one half inch so as not to waste any filling and then the two separate webs are separated by the knives 28 so that 110 both webs may travel their respective courses over their respective sand roller systems. The sand roller take-ups are each driven in the usual manner, but by separate trains of gears, from the respective pick wheels which, 115 in turn, are driven, as one, from a catch operated by the motion of the lay.

The U-shaped members 27 have their ends secured to brackets 29 (see Figure 2) slidable on the mounting members 30 carrying guide rods 31 provided with springs 32 which permit the said shuttle race 10 to be moved by hand to the position indicated in dotted lines shown in Fig. 2 so that the weaver may draw the shuttle race 10 out of the way when 120 working on the goods. In order not to conceal other details, these parts 28 to 32, inclusive, have been eliminated in Fig. 1, the location of the U-shaped members 27 only being indicated. For a similar reason the 125 130

brackets 29 have been removed from the U-shaped members 27 in Fig. 4.

The mounting members or guides 30 are pivoted to adjustable hinges 40 secured to the forward end of the lay 8 and have slideable connection with the rods 41 which are pivoted on hinges 42 secured on the forward end of the breast beam. In this manner the device is given freedom to move back and forth with the lay when the loom is running. Accordingly the raceway 10 will have two independent motions. The one for the purpose of permitting the weaver to work on the goods to put in ends or ripping floats when he moves the raceway 10 back by hand, together with the rods 27 and brackets 29, sliding therein on the guides 30, which then remain stationary, together with the rods 41 and hinges 42. The raceway 10 receives a second movement in horizontal direction during the operation of the loom when the raceway 10, together with the rods 27, brackets 29, guides 30, rods 41 and hinges 40, 42, oscillate with the lay. The filler boards 10' of the upper shuttle race are secured by bolts 33 carrying springs 34 to the reed holding board, the said springs 34 maintain the filler boards 10' in proper position but permit of their being lifted, when necessary to release the bottom shuttle.

The shuttle boxes are constructed for right and left hand sides of the loom and are opened at the back to accommodate a double picker 35 having the body thereof vertically passaged to receive the picker stick, a roller 36 being fitted in the forward or striking end of the picker and held by a steel pin suitably secured in place, the purpose of the roller 36 being to give the same leverage for striking both shuttles to prevent, as far as is possible, undue wear on the picker stick. The picker body 35 carries two butt recesses 37 and 38 each having a rawhide butt or picker block 37', 38' forced thereinto as indicated at 37' and 38' respectively for running in both levels of the shuttle box. The shuttle box guide ends 40 are shaped to receive the picker body at such time as the shuttle boxes are changing levels.

50 The double pickers 35 are easily removable so as to be substituted by single pickers to obviate the necessity of running both shuttles constantly should one warp run off before the other.

55 I claim:

1. In a double shed loom, a lay beam having a lower raceway for the lower shed, and an upper raceway independently mounted for the upper shed and slideable in its own plane.

2. In a double shed loom, a lay beam having a lower raceway for the lower shed, and an upper raceway independently mounted for the upper shed and slideable in its own plane, and supplemental raceways suspend-

ed from said lay beam and extending between the shuttle boxes and the ends of said upper raceway.

3. In a double shed loom, a lay beam having a lower raceway for the lower shed, and an upper raceway for the upper shed independently mounted and slideable in its own plane, and yieldable means for permitting reciprocation of said upper raceway in transverse direction of the lay beam. 75

4. In a double shed loom, a lay beam having a lower raceway for the lower shed, and an upper raceway for the upper shed, independently mounted and slideable in its own plane, yieldable means for permitting reciprocation of said upper raceway in transverse direction of the lay beam, and a pair of knife members mounted at the extremities of the said upper raceway adapted to sever the connecting threads at the 85 selvage edge between the webs formed by said upper and lower sheds.

5. In a double shed loom, a lay beam having a lower raceway for the lower shed, and a slideable upper raceway independently 90 mounted for the upper shed, and supplemental raceways extending between the shuttle boxes and the ends of said upper raceways and suspended from said lay beam.

6. In a double shed loom having the sheds superposed with relation to each other, a pair of shuttle boxes situated one on each side of the sheds, each of said shuttle boxes being provided with three superposed compartments, and means for positioning the middle compartment of one shuttle box opposite the upper shed while simultaneously positioning the middle compartment of the other shuttle box opposite the lower shed and for alternating said positions and a raceway for each shed, one of said raceways being slideable in transverse direction with relation to the sheds. 105

7. In a double shed loom having the sheds superposed with relation to each other, a pair of shuttle boxes situated one on each side of the sheds, each of said shuttle boxes being provided with three superposed compartments, means for positioning the middle compartment of one shuttle box opposite the upper shed while simultaneously positioning the middle compartment of the other shuttle box opposite the lower shed and for alternating said positions, and means for simultaneously sending a shuttle 110 from each box through the shed to the opposite box and a raceway for each shed, one of said raceways being horizontally slideable in transverse direction with relation to the sheds. 115

8. In a double shed loom having the sheds superposed with relation to each other, a pair of shuttle boxes situated one on each side of the sheds, each of said shuttle boxes being provided with three superposed com- 120

4
parts, means for positioning the middle compartment of one shuttle box opposite the upper shed while simultaneously positioning the middle compartment of the other shuttle box opposite the lower shed and for alternating said positions, and means for simultaneously sending a shuttle from each box through the shed to the opposite box, said shuttle sending means comprising a picker for each box with a pair of butts

spaced apart the same distance as said compartments, the lower butt registering with the lowermost compartment when said box is in its upper position and a raceway for each shed, one of said raceways being horizontally slidably in transverse direction with relation to the sheds. 15

In testimony whereof I affix my signature.

CLYDE A. COOK. [L. s.]
